(57) **CLAIM**

The ornamental design for an air flow directing and controlling fixtures for heating, air conditioning and ventilation devices, as shown and described.

DESCRIPTION

FIG. 1 is an isometric view of the air flow directing and controlling fixture, with the vanes closed, showing our new design;

FIG. 2 is a top plan view thereof with the vanes closed;
FIG. 3 is a first side elevational view thereof, with the vanes closed, the opposite side being a mirror image thereof;
FIG. 4 is a left end elevational view thereof, with the vanes closed;

FIG. 5 is a right end elevational view thereof;

FIG. 6 is a top plan view thereof, with the vanes open;
FIG. 7 is a first side elevational view thereof, with the vanes open, the opposite side being a mirror image thereof; and,
FIG. 8 is a bottom plan view showing the vanes open.
